UNITED STATES PATENT OFFICE.

BERNARD FUHRER, OF NEW YORK, N. Y.

TRAFFIC SIGNAL

Application filed November 18, 1927. Serial No. 234,216.

This invention relates to traffic signals and my improvements are directed to means whereby the flow of traffic may be automatically regulated and varied according to the 5 particular circumstances surrounding the problem.

At the present time, the problem of traffic control has been partially solved by the stationing of traffic directors at intersecting 10 streets and also by the installation of elaborate systems of signals extending along arterial highways generally leading from the centers of dense population to outlying sections. The former method, sometimes termed humanly controlled traffic, requires the expenditure of considerable manual labor, while the latter entails the adoption of a complicated and expensive system.

In an attempt to advance the solution of 20 this problem I have developed a traffic signal which substantially is a unit within itself. That is, the operating power therefor is a part thereof and while the device may be positioned in series along a thoroughfare, the 25 working of the same is not directly responsive to its companion, though in operation the series will respond to the particular setting of the signal. In other words, the long lines of conduits and connections, now in use, are 30 dispensed with and the failure of one to operate does not in any way affect the remainder of the signals.

Another problem confronting the traffic director is the positioning or locating of the 35 signals at intersections and while some instances permit the placement of these devices centrally of the intersections, quite frequently it is necessary to station the signals at the corners. In the first instance, assuming now 40 that an automatic signal is used, a place therefor may be found centrally of the intersection and in this case said signal may comprise a casing having a cruciform shape. However, in other instances the signals must 45 be placed at the corners, as aforesaid, the casings having oppositely directed sight openings to take care of, let us say, north and south traffic, while the east and west traffic is controlled by a similar device preferably 50 located at a diagonal corner.

My device has been adapted to meet these cases and while the preferred embodiment, as shown in the drawings, depicts a casing having oppositely arranged openings, it will of 55 course be understood that the slight modification necessary to change the device into a

signal for use at central points along intersections, is within the realm of the invention.

Another feature of the invention resides in the susceptibility of the signal for variation 60 in order to meet the degree of traffic flowing through a given intersection. Thus, in instances where the north and south traffic is greater than the east to west traffic, the intervals of starting and stopping the movement of vehicles should be in conformity with 65 the traffic, and this regulating is accomplished by the use of timing gears, as will presently appear.

The invention is further featured by its 70 low cost of production and the extremely reasonable installation and maintenance expense. The device is positive in operation and after setting requires but little attention on the part of the operator.

With these objects in view, together with others which will appear as the description proceeds, the invention resides in the novel formation, combination, and arrangement of parts, all as will be described more fully 80 hereinafter, illustrated in the drawings, and particularly pointed out in the claims.

In said drawings:

Figure 1 is a front elevation of the casing 85 the preferred arrangement of two sight openings being shown.

Fig. 2 is a horizontal central sectional view through the casing shown in Fig. 1, some of the operating parts being shown in plan.

Fig. 3 is a front elevation of the casing 90 which is similar to that shown in Fig. 1, with the exception that four sight openings are used.

Fig. 4 is a vertical central sectional view of the casing shown in Fig. 3, with the operating parts in elevation, said view being 95 slightly enlarged and partly broken away.

Fig. 5 is a detail view of an operating disk.

Fig. 6 is a sectional detail of one of the timing gears, and

Fig. 7 is a detail view of the rotatable screens.

Referring now in detail to the accompanying drawings, wherein like characters of reference denote similar parts throughout the 105 several views, let 15 denote generally the body portion of the casing, which comprises the intermediate portion 16 and two similar end portions 17 and 18, each being joined to said intermediate portion by flanging the abutting surfaces thereof and securing together 110 by means of screws or other fastening means,

as indicated at 19 and 20. This construction will readily be understood upon inspection of Fig. 2 and it will be noted that such an arrangement permits convenient access to the casing, at either end, in the event repairs or replacements are to be made, or the casing cleaned interiorly.

The front portions of each of the ends 17 and 18 are depressed inwardly to form a rim 21 which bears against a portion of the lens 22, adjacent the periphery thereof, while partitions 23, secured to the end portions 17 and 18, as indicated at 24 and 25, abut the opposite marginal sides of said lens 22, and centrally support the latter by means of the bolts 26 and 27 passing through apertures disposed in both lens and partitions. As shown in Fig. 1, the lens, at both ends of the casing, are provided with bulging portions 28 and 29, disposed in the same horizontal plane and lying directly over apertures 30 and 31 formed in partitions 23. Thus light from any source of illumination within the casing may only be seen through these openings.

The casing disclosed above is thus provided with oppositely disposed end portions, each having a pair of exposed openings, this type of casing being adaptable for mounting at diagonal corners of intersections, and as will presently appear it is my idea to intermittently show a red or green light through said openings by means of a rotatable screen under control of certain mechanism.

The mechanism for controlling the rotatable screens 32 and 33, is inclosed in a housing 34, see Fig. 2, which has been shown as removed in Fig. 4, said mechanism comprising a clock-work, partially shown somewhat diagrammatically, supported by standards 35 and 36, secured to the casing as indicated at 37, the power from the mechanism intermittently rotating a stub shaft 38 extending a short distance beyond said standards 35 and 36, (see Figs. 2 and 4). At this time attention is directed to the fact that the mechanism or parts about to be described are duplicated in the device. That is, the set of parts extending to the right and left of the mechanism contained in the casing 34, operate in unison to direct information to the oppositely flowing traffic, and in view of this duplication and similar mode of operation, only one set will be described in detail as follows.

Rotatably connected to said stub shaft 38 is a selector element 39 having a socket portion 40 to effect said connection, and being provided with diametrically opposed arms 41 and 42 having lateral projections 43 and 44 cooperating with a control disk 45 carried by shaft 46 mounted in bearing 47, the outer end of said shaft 46 carrying in one instance the screen 32. The coupling up of said shafts 38 and 46, for the ultimate rotation of either screen 32 or 33, is effected by the engagement

of the lateral projections 43 and 44 with ears 48 and 49 oppositely disposed on the periphery of said disk 45 (see Fig. 5), as will be pointed out during the discussion of the operation of the signal.

The bearing 47 rises from a standard 50 having its base portion 51 suitably secured to the casing, and for the screens 32 and 33, it will be observed that each comprises two oppositely disposed units 52 and 53 embodying rims 54 and 55 supporting green and red glass 56 and 57, respectively, and joined by the medial portion 58 formed with a boss 59 fixedly carried by said shaft 46. These screen units are, of course, adapted to be timed for rotation in front of openings 30 and 31 and in view of the illuminating means 60, suitably arranged within the casing the colors of the screens may be seen through the lens 22 at suitable intervals. In the form of lens shown in Fig. 3, four openings will be provided in the partitions 23 which will necessitate the provision of the two vertically disposed bulged portions 61 and 62. In other respects the device is quite similar.

The power to drive the mechanism may be any power known to be adaptable to that purpose. In this instance a key 63 has been shown which may be manually operated to wind a suitable spring arrangement carried in a closure 64, secured to a toothed wheel 65, mounted on shaft 66, the teeth of which mesh with a lantern pinion 66 operatively connected to shaft 38. Upon inspection of Fig. 6, it will be observed that said wheel 65 is provided with sixteen peripheral teeth 68, equally spaced, and when one of these teeth contact with any one of the rods 69, it will require sixty seconds to pass same and at the moment of its passing the next tooth contacts with another rod, but the spring (or other source of power), causes the wheel 65 to exert its full power on shaft 38, thus turning the selector element 39 snap fashion, causing the projections 43 and 44 to contact with ears 48 and 49 of control disk 45 and finally rotating the screen units 52 and 53 to either a horizontal or vertical position as the setting of the operating will permit.

If necessary I may apply any well-known form of registering or stopping means in order to assure the proper alinement of the screen units. The remainder of the gears and wheel devices in the driving mechanism simply act as a shock absorber when the gear 65 leaves the rods of the lantern pinion.

In the cruciform arrangement, I propose to provide the stub shaft 38 with bevel gears which may enmesh with a pair of oppositely disposed gears mounted on suitable shafts extending at right angles to said shaft 38 and terminating with screen units, as in my preferred form.

While the present is a disclosure of the preferred embodiment of the invention, it is

to be understood that the invention is not limited thereto as various changes in the minor details of construction, proportion and arrangement of parts may be resorted to 5 without departing from the spirit of the invention as defined in the appended claims.

I claim:

1. In a traffic signal, a casing presenting a series of openings disposed in the opposite 10 sides thereof, a double unit screen member adapted to rotate before each of said openings for exhibiting a selected color signal and means for intermittently and simultaneously operating said screens.
- 15 2. In a traffic signal, a casing presenting an intermediate portion and two end portions, each of said end portions being provided with a series of oppositely disposed openings, rotatable screen members adapted to exhibit 20 a selected color signal through a selected opening and means for intermittently and simultaneously operating said screens.
- 25 3. In a traffic signal, a casing presenting a series of openings disposed in the opposite ends thereof, screens located inwardly of each series and adapted to exhibit color signals

in opposite directions and means positioned intermediate said screens and adapted to intermittently and simultaneously align the same with selected openings.

4. In a traffic signal, a casing comprising an intermediate portion and end portions having a series of oppositely disposed openings therein, lens removably mounted before said openings, rotatable screens comprising 35 units and adapted to exhibit a selected color signal through said openings, and means for intermittently operating said units and comprising timing gears variably synchronized.

5. In a traffic signal, a casing comprising an intermediate section and end portions, partitions mounted in said end portions and having a series of openings, a lens removably positioned in front of each opening, rotatable screens comprising units adapted to exhibit 45 a selected color signal through a selected opening and means for intermittently operating said screens and to position the same in alignment with said openings.

In testimony whereof I affix my signature.

BERNARD FUHRER.
